UNITED STATES PATENT OFFICE

SAMUEL E. SPERRY, OF HOLLIS, NEW YORK, ASSIGNOR TO INTERTYPE CORPORATION, OF BROOKLYN, NEW YORK, A CORPORATION OF NEW YORK

SLUG-TRIMMING KNIFE

Application filed March 24, 1928. Serial No. 264,354.

The present invention relates to improvements in knives for trimming the sides of slugs or type bars produced in line casting machines to bring such slugs to the proper thickness to conform with desired type sizes. Heretofore, it has been customary to cast slugs which varied in thickness in accordance with the full point sizes employed generally in the printing art to designate standard type sizes, and the knives used in line casting machines have consequently been provided with means for setting them in accordance with such full point or standard type sizes in order to trim the sides of the slugs and thus bring them to the exact full point or standard sizes for which the knives were set.

A demand for type faces which will permit of condensing printed matter however has called into service matrices or matrix characters of fractional point sizes, this being especially so in the smaller type commonly used in newspaper printing, and it has been found desirable to cast such fractional size type faces on slugs which are trimmed to corresponding fractional points of thickness.

The primary object of the present invention is to provide means whereby the slug trimming knife of a line casting machine may be set to trim the slugs or type bars to such fractional point sizes with the same speed and facility as has been possible in the setting of such knives for the usual or full point sizes.

Another object is to provide means of this character which is capable of being applied to trimming knives on existing line casting machines or to trimming knives of the kinds heretofore used, with minimum change, labor and expense, and without weakening or impairing the accuracy of setting of such knives.

To these and other ends, the invention consists in certain improvements and combinations and arrangements of parts all as will be hereinafter more fully described, the features of novelty being pointed out particularly in the claims.

In the accompanying drawings:—

Fig. 1 is a perspective view of a portion of

a slug trimming knife embodying fractional point setting means therefor in accordance with the present invention;

Fig. 2 represents on an enlarged scale an elevation of the setting means shown in Fig. 1 as viewed from the right in that figure;

Fig. 3 is a top view of the setting device, parts thereof being shown in section or broken away;

Fig. 4 represents a section taken radially through the knife adjusting member and the cooperative setting device, the setting device being shown engaged with the adjusting member in full lines and disengaged therefrom in dotted lines;

Fig. 5 represents a section taken on the line 5—5 of Fig. 4 and looking in the direction of the arrows; and

Fig. 6 is a diagrammatic view illustrating how the knife adjusting member is set for trimming slugs to the usual full point size and for different fractional point sizes.

Similar parts are designated by the same reference characters in the several views.

Slug trimming knives of the general class to which the present invention is applied are used in typographical machines of the class shown and described in Letters Patent No. 436,532 granted September 16, 1890 to O. Mergenthaler, the knife being positioned to receive each slug or type bar as it is ejected from the mold in which it is cast and operative to trim the sides of the slug so that each slug will be of the exact thickness or type size for which the knife is set. The invention is shown in the present instance as applied to a slug trimming knife of the kind shown and described in Letters Patent No. 1,426,231 granted August 15, 1922 to S. E. Sperry, to which reference is made for a disclosure of the complete construction and mode of operation of the knife.

For the purposes of the present invention, it is believed sufficient to point out that 1 represents the knife block which is adapted to be bolted or otherwise secured rigidly to the frame of the machine, the knife block carrying a movable knife blade adapted to be arranged opposite to a stationary knife blade, the space between the knife blades providing a passageway through

55

95

100

which the slug is forced while it is being ejected from the mold, and the knife blades acting to trim the sides of the slug to the proper thickness of type size. The movable knife blade is adjusted in a direction toward or from the stationary blade, in setting the knife to trim slugs to different thicknesses or type sizes, by an adjusting member 2 which is in the form of a ring which is attached to a screw which is threaded in the knife block and serves, when rotated, to set the movable knife blade at different distances from the stationary knife blade as will be understood from the Sperry patent above referred to.

15 The adjusting member 2 is formed with a set of grooves or notches 3 which are graduated or spaced circumferentially of said member in accordance with the settings of the movable knife blade for the trimming of the slugs to the usual or full point thicknesses.

20 Heretofore, an ordinary latch or detent was mounted on the stationary knife block and was engaged with one or another of the grooves or notches in the adjusting member, the detent being thus capable of setting and holding the adjusting member in any one of a number of positions each of which however corresponded with a usual full point type size. The present invention provides means 25 whereby the knife-adjusting member can be set not only for the various usual full point type size but can also be set for the trimming of slugs to fractional point sizes. It comprises a detent member for holding the adjusting member in different adjusted positions, one of these members having graduations thereon which correspond with fractions of the usual full point type sizes whereby the knife may be set not only for the usual full point sizes but also for fractional 30 point sizes. The preferred setting means as shown in the present instance comprises a multi-toothed detent, the teeth thereof being relatively differently located, and the detent 35 may be manipulated so as to bring any one of its teeth into engagement with any one of the grooves or notches 3 in the knife-adjusting member, the relatively different locations of the teeth of the detent corresponding 40 with settings of the adjusting member at fractional point sizes so that when a selected tooth of the detent is engaged with a selected groove or notch in the adjusting member, the latter will be set for the full point setting 45 corresponding with the engaged groove or notch plus the fractional point setting represented by the tooth of the detent which engages such groove or notch.

50 The detent, as shown, comprises a bracket 4 which may be secured to the knife block 1 by the screws 5, in the same position but as a substitute for the detent previously used, the bracket being secured to a part of the knife block opposite to the adjusting ring or member 2 and a portion of the bracket overlying

the grooved or notched periphery of said ring or member. The overhanging portion of the bracket is formed with a slot 6 which is radial to the adjusting ring 2, and this slot is adapted to receive and accurately fit any one of a number of blades which carry the differently located teeth of the detent. Preferably, the multi-toothed detent comprises a member 7 having blades 8 projecting radially from its center, the blades being of a number corresponding with the number of fractional settings which it is desired to secure. The member 7 is formed with a sleeve-like handle 9 which extends beyond the end of the bracket which overhangs the adjusting ring 2, this handle being alined with the axis of the member 7 and it may be knurled at its extremity, as shown, so that it may be gripped and turned by the fingers of the operator. The member 7 is revolvably mounted on a shaft 10, and the latter is pivotally connected to the bracket 4 by a transverse pin 11 so that the shaft and the detent member thereon may be swung from the full line position to the dotted line position shown in Fig. 4 and vice versa. While the detent member occupies the dotted line position shown in Fig. 4, it may be rotated to bring any one of its blades into alinement with the slot 6 in the bracket, and the detent member may then be swung into the full line 90 position shown in Fig. 4, the selected blade of the detent member entering the slot 6 and being accurately positioned therein.

95 Each blade 8 of the detent member 7 is provided with a tooth or rib 12 on its lower or peripheral edge which is adapted to fit closely into one or another of the grooves or notches 3 in the adjusting member 2, but these teeth are located differently on the different blades to conform with different fractional point settings of the adjacent member 2. For example, as in the present instance where the detent is adapted for the setting of the knife adjusting member 2 for the trimming of slugs to the usual full point size and to 100 quarter fractional sizes, the detent member 7 is formed with four blades and the teeth 12 on the different blades are located in different positions on the outer edges of these blades to conform with the respective settings 105 of the adjacent member 2 for the corresponding fractional point type sizes. By reference to the diagram shown in Fig. 6, it will be observed that the tooth on the blade marked "1" registers with the selected groove 3 in the adjacent member 2 when said groove 110 has been brought to the point indicated by the line 13, the adjusting member being then set to position the knife blades so that the slugs will be trimmed to a usual full point size. When the tooth on the blade marked 115 "1/4" is engaged with a groove 3 in the adjusting member, said groove will occupy the position indicated by the line 14, and the adjusting member will then set the knife to trim 120

125

130

the slugs to a quarter of a size larger than the full point size corresponding with the setting 13. Similarly, when the tooth of the blade marked "1/2" or the tooth marked "3/4" is 5 engaged with the groove or notch 3 in the adjusting member 2, said groove or notch will occupy the position indicated by the line 15 or the line 16 respectively, and the adjusting member will then be set for the trimming 10 of slugs one half or three quarters of a size larger than the setting represented by the line 13.

The detent may be readily rotated by means of its sleeve 9 to bring any one of its blades 15 into position to enter the slot 6 in the bracket and to engage the adjusting member 2, when the detent is swung into the dotted line position shown in Fig. 4. Means is preferably provided for yieldingly retaining the detent 20 either in said dotted line position to facilitate rotation of the detent or in the full line position shown in Fig. 4 and thus maintain the detent in locking engagement with the adjusting member 2. Such means is shown in the 25 present instance, it comprising a compressed spring 17 one end of which abuts against a wall 18 of the bracket 4 and the opposite end of which abuts against a crank arm 19 which is rigid with the shaft 10 and extends at an 30 angle thereto, the pressure of the spring against the crank arm 19 acting to maintain the detent in its operative position as shown by the full lines in Fig. 4 and the pressure of the spring acting on the crank arm to maintain 35 the detent in its inoperative position as shown by the dotted lines in Fig. 4 after the detent has been shifted into that position. Excess movement of the detent past its raised or inoperative position is prevented by the 40 engagement of the crank arm 19 against the bottom wall of the bracket 4. A rod 20 may be pivotally connected at 21 to the spring-engaged end of the crank arm 19 and may 45 reciprocate through and rock in an opening 22 formed in the rear end of the bracket 4, this rod occupying a position within the spring, which is preferably of the helical or coiled type, and serving to maintain the spring in proper position.

Knife setting means constructed as hereinbefore described enables the knife to be set for fractional point sizes with the same speed and facility as is possible in the setting of such knives to the usual full point size. To 55 set the adjusting member 2 for any fractional point type size, it is only necessary for the operator to swing the detent from the full line to the dotted line position shown in Fig. 4 and rotate the detent to bring the 60 blade bearing the desired fractional designation into alignment with the slot 6 in the bracket, to rotate the adjusting member 2 to bring the selected groove or notch 3 therein beneath the slot 6 and to then return the 65 detent to the full line position shown in Fig.

4 engaging the tooth on the selected blade of the detent in the selected groove or notch in the member 2. For example, if it is desired to set the knife to trim slugs to a thickness of 5½ points, the detent is rotated to bring the blade marked "1/2" into position to enter the slot 6 and the adjusting member 2 is rotated until the groove or notch therein corresponding with the full 5 point setting is registered with the tooth on the selected detent blade, and when the detent is moved into its operative or locking position, the adjusting member 2 will be set so that the knife will trim the slugs to a thickness of 5½ points. Any other fractional settings and the full point settings are made in a similar way, the rotation of the detent determining the fractional or full setting of the adjusting member 2.

If desired, a pair of stops 23 may be mounted shiftably around the circumference of the adjusting member 2 and locked thereon by dogs 24 for the purpose of enabling the operator to quickly adjust the knife to one or another of two commonly used settings, 85 these limit stops being locked by the dogs 24 at the appropriate points around the circumference of the member 2 and adapted to abut against one or the other side of the overhanging portion of the bracket 4 of the detent 90 when the adjusting member 2 has been brought into one or the other of the two positions for which the stops are set. One of these limit stops, preferably the one exposed at the front of the machine, may be provided 95 with a handle 25 which will serve as conveniently accessible means for rotating the adjusting member 2 during the setting of the knife, this handle being relatively short radially so that it will not interfere with other 100 parts of the machine in which the knife is used.

Knife setting means embodying the present invention may be applied to slug trimming knives to enable them to be adjusted 110 to trim slugs to fractional point sizes as well as the usual full point sizes, without weakening the knives or impairing the accuracy thereof, as the adjusting member will be accurately set and securely held in each of its various positions, and the particular setting means shown may be readily and inexpensively applied to line casting machines which are in use, as the detent employed in this construction herein described may be substituted for the detent previously employed, for full point settings, thereby adapting such knives to the trimming of slugs 120 to fractional point settings as well as to the usual full point settings.

The preferred embodiment of the invention has been shown and described, but it is to be understood that equivalent constructions may be used, and such are included, within the scope of the claims.

I claim as my invention:—

1. In a slug trimming knife for line casting machines, the combination of an adjusting member for adjusting the knife to trim slugs to different sizes, and a setting member cooperative therewith, one of said members having setting-controlling graduations which correspond with full point type sizes, and one of said members having other setting-controlling graduations which correspond with fractions of such full point sizes.

2. In a slug trimming knife for line casting machines, the combination of a rotatable member for adjusting the knife to trim slugs to different sizes, and a member cooperative with said rotatable member for setting it in different adjusted positions, the rotatable member having setting-controlling graduations which correspond with full point type sizes, and one of said members having other setting-controlling graduations which correspond with fractions of such full point sizes.

3. In a slug trimming knife for line casting machines, the combination of an adjusting member for adjusting the knife to trim slugs to different sizes, and a detent member for setting and holding the adjusting member in different adjusted positions, one of said members having setting and holding graduations which correspond with full point type sizes, and one of said members having other setting and holding graduations which correspond with fractions of such full point sizes.

4. In a slug trimming knife for line casting machines, the combination of a rotatable adjusting member for adjusting the knife to trim slugs to different sizes, and a detent member for setting and holding the adjusting member in different adjusted positions, the adjusting member having setting and holding graduations thereon which correspond with full point type sizes, and one of said members having other setting and holding graduations which correspond with fractions of such full point sizes.

5. In a slug trimming knife for line casting machines, the combination of a member having graduations which correspond with settings of the knife to trim slugs to full point type sizes, and a detent having portions which conform with fractional size settings of the knife and movable to bring one or another of said portions into cooperation with the graduations on said member.

6. In a slug trimming knife for line casting machines, the combination of a member having graduations which correspond with full point type size settings of the knife, and a detent having relatively differently located portions which correspond with fractional size settings of the knife and one or another of which may be brought into cooperation with the graduations on said member.

7. In a slug trimming knife for line casting machines, the combination of a member

for adjusting the knife to trim slugs to different sizes and having graduations thereon corresponding with full point type sizes, and a detent member having portions graduated to correspond with fractions of such full point sizes and one or another of which graduations may be brought into cooperation with the graduations on the adjusting member.

8. In a slug trimming knife for line casting machines, the combination of a member for adjusting the knife to trim slugs to different sizes and having graduations spaced thereon to correspond with full point type size settings of the knife, and a detent member having a plurality of portions one or another of which may be brought into cooperation with the graduations on the adjusting member, said portions of the detent member being relatively differently located to correspond, when in cooperation with the graduations on the adjusting member, to fractional size settings of the knife.

9. In a slug trimming knife for line casting machines, the combination of a member for adjusting the knife to trim slugs to different sizes and having notches therein which are spaced to conform with full point type size settings of the knife, and a multi-toothed detent movable to bring any one of its teeth into engagement with a notch in said member, the teeth of the detent being relatively differently located to correspond, when engaged with a notch in said member, with fractional size settings of the knife.

10. In a slug trimming knife for line casting machines, the combination of a knife-adjusting member having notches therein spaced to correspond with different full point type size settings of the knife, and a cooperative detent having a plurality of teeth thereon which are relatively differently located to correspond with fractional size settings of the knife, said detent being movable toward and from said member to engage and disengage one of its teeth with respect to a notch in said member and being rotatable, while disengaged from said member, to bring one or another of its teeth into position to engage said member.

11. In a slug trimming knife for line casting machines, the combination of a knife-adjusting member having notches therein corresponding with different adjustments of the knife, a relatively fixed bracket adjacent to said member and having a slot therein, and a multi-bladed detent movable with respect to said bracket to bring one or another of its blades into said slot, the blades of the detent having relatively differently located teeth thereon to respectively engage in one or another of the notches in the adjusting member.

12. In a slug trimming knife for line casting machines, the combination of a knife ad-

justing member having graduations thereon corresponding with different adjustments of the knife, a relatively fixed bracket adjacent to said member and having a slot therein, a 5 detent member having a plurality of radially-arranged blades each adapted to fit into said slot in the bracket, said blades having relatively differently located teeth thereon corresponding with different adjustments of the 10 knife and adapted to cooperate with the graduations on the adjusting member, and means for supporting the detent to move toward and from the adjusting member and for rotation to bring one or another of its blades into 15 position to enter the slot in the bracket.

13. In a slug trimming knife for line casting machines, the combination of a knife adjusting member having graduations corresponding with different adjustments of the 20 knife, a detent having a plurality of relatively differently located teeth each adapted to cooperate with one or another of the graduations on the adjusting member, means supporting the detent for rotation to bring 25 one or another of its teeth into operative position and for movement to and from cooperative relation with the adjusting member, and means for yieldingly holding the detent in operative and inoperative positions relatively 30 to the adjusting member.

14. In a slug trimming knife for line casting machines, the combination of a knife-adjusting member, means for holding said member in different adjusted positions, and a 35 limit stop having means for fixing it in different positions on said member and having a handle thereon adapted to serve as means for shifting said adjusting member.

In testimony whereof I have hereunto set
40 my hand.

SAMUEL E. SPERRY.
